CLAIM

The ornamental design for a monitoring camera as shown and described.

DESCRIPTION

FIG. 1 is a perspective view of a monitoring camera showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken lines represent portions of the monitoring camera that form no part of the claimed design.
